US00D844636S

(12) **United States Design Patent** (10) **Patent No.:** **US D844,636 S**
Kim et al. (45) **Date of Patent:** **** Apr. 2, 2019**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Soomin Kim**, Seoul (KR); **Moonjeong Kim**, Ulsan (KR); **Taekyeung Lim**, Seoul (KR); **Joonho Ok**, Seoul (KR)

(73) Assignee: **SAMSUNG ELECTRONICS CO., LTD.**, Suwon-si (KR)

(**) Term: **15 Years**

(21) Appl. No.: **29/628,093**

(22) Filed: **Dec. 1, 2017**

(30) **Foreign Application Priority Data**

Aug. 22, 2017 (KR) 30-2017-0039025

(57) **CLAIM**

The ornamental design for a display screen or portion thereof with graphical user interface, as shown and described.

DESCRIPTION

FIGURE is a front view of a display screen or portion thereof with graphical user interface showing our new design.

The outer perimeter shown in broken line in the FIGURE illustrates a display screen or portion thereof and forms no part of the claimed design. The remaining broken lines in the FIGURE illustrate portions of the graphical user interface that form no part of the claimed design.

1 Claim, 1 Drawing Sheet
